(57) **CLAIM**

The ornamental design for a liquid cooling cold plate with diamond cut pin fins, as shown and described.

DESCRIPTION

FIG. 1 is a top perspective view of a liquid cooling cold plate with diamond cut pin fins showing our new design; FIG. 2 is a top perspective disassembled view corresponding to FIG. 1;

FIG. 3 is a bottom perspective disassembled view corresponding to FIG. 1;

FIG. 4 is a left side elevational view thereof;

FIG. 5 is a right side elevational view thereof;

FIG. 6 is a rear elevational view thereof;

FIG. 7 is a front elevational view thereof;

FIG. 8 is a top plan view thereof; and,

FIG. 9 is a bottom plan view thereof.

1 Claim, 9 Drawing Sheets
